MICHAEL TRESCHOW, OF HELLERUP, DENMARK.

COMBINATION WITH SMOKE-TUBE BOILER.

Applicataion filed September 28, 1926, Serial No. 138,353, and in Denmark November 21, 1925.

It is a well known arrangement in smoke-tube boilers that the gases after having passed through the first row or the first rows of smoke tubes are reversed in a return chamber located, wholly or partly, outside the water space of the boiler, and from the said chamber pass into the next smoke passage, or in the case of a boiler having tubes through which the gases only pass in one direction, 10 that the gases are carried to a smoke box located, wholly or partly, outside the water space of the boiler, and from the said smoke box are conducted to the chimney through a smoke pipe or smoke flue, said return chamber or smoke box being removable for the purpose of giving access to the boiler tubes for cleaning the same.

On account of the high temperature of their exterior surfaces such return chambers 20 or smoke boxes, particularly the former, will always cause a great loss of heat and an inconvenient temperature in the boiler room. The usual remedy against these drawbacks is the appliance of some non-conducting material. But an effective covering has been made difficult by the high temperature prevailing, and the result obtained is so negligible that such coating very often is wholly abandoned.

30 The object of the invention is to reduce substantially the loss of heat from the said return chambers or smoke boxes of tubular boilers by transmitting the waste heat given off by the return chambers and smoke boxes to the combustion air, either the secondary or the primary air, or to both. In this manner the air will become intensively heated, thus furthering an effective combustion of the gases developed in the fire, which is of special 35 importance when the fire is burning low, as in such case the secondary air, if not properly heated, will cause such a drop in the temperature in the combustion chamber as to render impossible a complete combustion of the gases, especially when bituminous fuel is used.

Through the heat radiated from the return chamber or smoke box of a boiler the combustion air may be heated to a far higher degree than if heated by flowing through pas-

sages which are wholly or partly in contact 50 with the boiler water, and the manner of heating the combustion air, as embodied in the present invention, is far more efficient than in the cases where the heating is effected by conducting the combustion air, in some well 55 known manner, through passages in the brickwork arranged in or above the combustion chamber, as the temperature in the latter by this arrangement is reduced to such an extent as to minimize the advantages gained 60 by heating the combustion air.

The transmission of waste heat to the combustion air from the return chamber or smoke box of the boiler is effected by providing air jackets surrounding the said return chambers 65 or smoke boxes in such a manner as to establish hollow spaces between the latter and the air jacket, and the combustion air is carried through these hollow spaces, either by means of the draft in the chimney or by forced 70 draft. For this purpose the hollow spaces communicate through one or several apertures with the boiler room and also with the combustion chamber of the boiler by a pipe or passage for discharging the warm, sec- 75 ondary air. In order to compel the combustion air to flow across the total heating surface of the return chamber the hollow space may be divided into passages by means of ribs directing the course of the air.

If the walls of the return chamber or smoke box have not been properly cooled down by the passage of the secondary air and consequently still possess a surplus of heat available for heating purposes the said 80 discharge pipe or passage may be continued down to the space below the grate of the boiler, thus making it possible to supply warm, primary air to the fire place. For this purpose a special discharge pipe may 85 90 also be arranged.

The drawing shows an example of how the invention may be applied, both in a smoke-tube boiler with exterior return chamber, and in a smoke-tube boiler with smoke 95 box.

Figs. 1 and 2 show two vertical sections of a vertical smoke-tube boiler with exterior

return chamber, at right angles to each other, Fig. 3 a section following the line A—B in Fig. 1,

Fig. 4 a top view of the return chamber 5 and

Fig. 5 a vertical section of a vertical smoke-tube boiler with smoke box, as seen from the front.

In the boiler shown in Fig. 1 *a* is the fire 10 space with the combustion chamber, *b* is the shell of the boiler, *c* the fire door, *d* the grate, *e* the smoke tubes communicating with the combustion chamber and with the removable return chamber *v*, *f* the smoke tubes 15 communicating with the return chamber and with the smoke chamber *r* and *g* a partition wall between the fire space and the smoke chamber. *h* is the wall of the return chamber *v*, *i* an outer wall spaced from the wall 20 *h* and forming therewith an air jacket enclosing the return chamber *v*, and *l* a pipe, see Fig. 2, establishing communication between the return chamber *v* formed by the air jacket *i* and the combustion chamber of 25 the boiler, and, if so desired, also with the space below the grate. A tight fit between the removable return chamber *v* and the top plate of the boiler is obtained in some well known manner, for instance through a sand 30 lock *m*. For lifting the return chamber or smoke box when the boiler tubes are to be cleared an eye bolt *t* may be fixed on the former adapted to be engaged by the hook of a trolley travelling on a rail suspended 35 from the ceiling (not shown), thus making it easy to remove the return chamber. The connection between the pipe *l* and the air jacket should be easily detachable and may, for instance, be effected by a sand lock at the 40 upper end of the pipe *l*, into which lock the end of an elbow *n* of the air jacket engages. From the pipe *l* the warm, secondary air may be carried to the combustion chamber *a* of the fire space through a pipe or passage *u* 45 situated in the smoke chamber *r*, and communicating with the combustion chamber by several pipes *w*.

Instead of connecting the pipe *l* both with the combustion chamber *a* of the boiler and with the space below the grate *d*, as shown in Fig. 2, the pipe *l* may open only into one of the named spaces.

In either case, namely, when the pipe *l* opens both into the combustion chamber *a* of the boiler and into the space below the grate *d*, or when the pipe opens only into the combustion chamber or only into the space below the grate, dampers may be provided as shown in Fig. 2 for regulating 60 the air flowing through the passage or pipe *l*.

The ribs *o*, see Figs. 1 and 4, are located in the air jacket *i*, and because of these ribs the combustion air is compelled to flow across the total heating surface of the return cham-

ber. The apertures *k* admit the cold air 65 into the air jacket *i*.

As the temperature in the return chamber of a smoke-tube boiler, see Fig. 1, is very high due to the fact that the gases in this case have only passed part of the heating 70 surface, the combustion air will become intensively heated on its passage through the hollow space between the return chamber *v* and the air jacket *i*.

In smoke-tube boilers which are not provided with return chamber and in which the gases are carried direct to a smoke box, as shown in Fig. 5, and consequently have travelled along the total heating surface of the boiler before entering the smoke box, the temperature in the latter will be comparatively low and the combustion air correspondingly less heated. Still, the amount of heat given off in this manner will be so large that the smoke box would cause a considerable loss of heat, if not prevented by the said combination. 85

In Fig. 5 *s* is the smoke box, the other letters corresponding with those indicated in Figs. 1 and 2. The smoke pipe *x* is connected 90 with the removable smoke box in some well known manner, making it easy to disconnect the latter and the smoke pipe *x*.

Having thus described my invention, what I claim is:—

1. The combination with a smoke-tube boiler having uptake tubes and downtake tubes, of a removable member forming a return chamber disposed outside of the boiler, and in communication with all of said tubes for receiving combustion gases from the uptake tubes and delivering said gases to the downtake tubes, the wall of said return chamber being enclosed by an air jacket communicating with the atmosphere through at least one aperture, and a pipe in communication with said air jacket and the fire box of the boiler thereby to utilize the waste heat of the return chamber for pre-heating the combustion air. 105

2. The combination with a smoke-tube boiler having uptake tubes and downtake tubes, of a removable member forming a return chamber disposed outside of the boiler, and in communication with all of said tubes for receiving combustion gases from the uptake tubes and delivering said gases to the downtake tubes, the wall of said return chamber being enclosed by an air jacket communicating with the atmosphere through at least one aperture, and a pipe in communication with said air jacket and the fire box of the boiler thereby to utilize the waste heat of the return chamber for pre-heating the combustion air, said air jacket being provided with a plurality of ribs dividing the same into inter-communicating passages so directed as to cause the incoming air to contact with prac- 110 115 120 125

tically the entire surface of the wall of the return chamber.

3. The combination with a smoke-tube boiler having uptake tubes and downtake tubes, of a removable member forming a return chamber disposed outside of the boiler, and in communication with all of said tubes for receiving combustion gases from the uptake tubes and delivering said gases to the 10 downtake tubes, the wall of said return chamber being enclosed by an air jacket commun-

cating with the atmosphere through at least one aperture, a pipe in communication with said air jacket and with the combustion chamber of the boiler and having a branch in communication with the space below the grate, and dampers for controlling the passage of air through said pipe and branch. 15

In testimony whereof I have signed my name to this specification.

MICHAEL TRESCHOW.
